VARIABLE ELECTRIC FILTER

Rudolf Rechnitzer, Budapest, Hungary, assignor
to Telefunken Gesellschaft für Drahtlose Tele-
graphie m. b. H., Berlin, Germany, a corpora-
tion of Germany

Application March 4, 1937, Serial No. 128,959
In Germany March 5, 1936

9 Claims. (Cl. 179—1)

The present invention is concerned with a variable electric filter which comprises ohmic resistances and reactances, and which is primarily intended for filters containing a plurality of 5 units or meshes and designed to insure tone or timbre control in receiver sets and amplifiers. According to the invention, the filter incorporates a resistance device whose ohmic resistance is a function of the current flowing therethrough 10 and which serves to regulate the limiting or cut-off frequency.

In the case of multi-mesh filters the present invention offers the advantage that for the actuation of a single resistance serving for changing 15 the current all of the resistances included in the filter are varied. In the case of a single-unit filter the present invention offers the advantage that changes in current caused by the resistance change causing the same could, for instance, be 20 used at the same time for volume control purposes. By the operation of a single resistance, it is thus possible to insure a faithful regulation of the acoustic volume pleasing to the ear. In other words, in accordance with the present invention 25 during passages of low volume intensity, the medium-pitched and the high-pitched notes are weakened more markedly than the low pitched notes.

In the drawing accompanying the specification, Figure 1 illustrates schematically the invention incorporating a circuit in which regulation of the tone is provided by a low pass filter; Figure 2 illustrates the invention applied to a circuit utilizing a series type of filter; Figure 3 is a diagrammatic representation of the circuit 30 incorporating the invention and utilizing the filter in the plate circuit of a tube; Figure 4 illustrates the invention in connection with a resistance coupling arrangement; and, Figure 5 illustrates the invention in a circuit wherein volume control is combined with tone control.

Fig. 1 shows a circuit organization in which regulation of the timbre or tone control is made feasible by the agency of low-pass filter 1, 2. For 45 this object the amount of direct current flowing through resistance 1 is adjusted by the aid of the potentiometer 4. As the direct current flow becomes smaller, the resistance of the various meshes of the filter grows, with the result that the limiting or cutoff frequency of the filter is 50 shifted in the direction of the lower frequencies.

While in the circuit scheme shown in Fig. 1 the filter is so connected that the characteristic falls slowly towards the high frequencies, the filter shown in Fig. 2 is of the "line" (series) type 55 so that the characteristic is caused to droop suddenly in the presence of a certain frequency. In the arrangement shown in Figure 2, auxiliary resistances 5 and 6 are provided in order to shut off the regulator current for the filter.

Also in this arrangement the cutoff frequency, when the intensity of the current is low, will be shifted in the direction of the lower frequencies.

In the arrangement shown in Fig. 3 the filter is included in the plate circuit of the tube. This 5 arrangement is less satisfactory than some of the other arrangements described herein for the reason that a change in the plate potential is occasioned at the same time.

Fig. 4 illustrates another embodiment which 10 resembles the scheme shown in Fig. 1, though it is here used in connection with resistance coupling. In order that the change in the value of resistance 1 caused by changes of current may not be conducive to a change in the gain, the 15 lowest value of the resistance 1 is preferably made higher than that of resistance 8.

Fig. 5 shows a circuit organization in which 20 volume control is combined with timbre or tone control. When the volume is comparatively low, a smaller part of the potentiometer is short-circuited for D. C. by the primary winding, with the result that the current flowing across the resistances 1 decreases. The value of the resistances 1 becomes greater as a consequence so that 25 the higher pitched notes will be attenuated more markedly.

It will be understood that there are many ways of incorporating the basic idea of this invention such as in connection with filters containing, for 30 instance, coils in lieu of condensers.

What I claim is:

1. In an audio frequency transmission system including means to connect the same to a source of audio frequency voltage and an audio frequency utilizing load, an electrical network for regulating the audio frequency transmission between the source and the load, said network including a filter unit provided with a resistance element the alternating current resistance of which is a function of the direct current component of current passing through it, a source of direct current connected across said last named resistance element and means for controlling the amount of current passing from said source through the last named resistance element.

2. In an audio frequency transmission system, means for connecting the system to a source of audio frequency voltage, an electronic tube having an anode, a cathode and an input grid electrode, a source of anode current for said tube, said source having a positive terminal and a negative terminal, a connection including a resistance element between the anode and the positive terminal of the source and means connecting the negative terminal and the cathode, a connection between the anode of the tube and the cathode thereof and including a condenser and at least two resistance elements in series, means for connecting said two resistance ele- 50 55 60

ments in series across said source of direct current whereby a flow of current is produced through said resistance elements, one of said resistance elements having an alternating current 5 resistance which is a function of the direct current component of current passing therethrough and means for varying the effective value of the said other series resistance which is in series between the first of said two series resistances and 10 the source of direct current to thereby control the flow of direct current through the first of said series resistance elements, a utilizing circuit and means for connecting the utilizing circuit across the second of said series resistance.

15 3. The combination with an audio frequency amplifier of a tone control circuit therefor including a filter network provided with means for giving to the filter network variable frequency characteristics, said means including a resistance device having an alternating current resistance which is a function of the direct current 20 component of current passing through it, a source of direct current, means connecting said resistance device across said source, said last 25 named means including variable means for controlling the amount of current flowing from the source through the resistance device.

4. In a tone compensated volume control device for an audio frequency amplifier including a 30 source of audio frequency voltage and an audio frequency utilizing load, a network connected between the source and the utilizing load, said network including a resistance having an alternating current resistance which is a function of direct 35 current component of current caused to flow through it and acting to vary the frequency characteristics of the filter circuit and means included in the network for controlling the amount of audio frequency current transferred from the 40 source to the utilizing load, operation of the last named means also acting to vary the direct current component of current flowing through the filter network.

5. In an audio frequency amplifier, an electronic 45 tube provided with an input circuit and an output circuit, means for connecting the input circuit to a source of audio frequency voltage, an audio frequency utilizing load, a source of anode direct current for said tube, said source being connected in the output circuit thereof, a filter network in said output circuit for regulating the audio frequency transmission through the output circuit, said filter network including a resistance element having an alternating current 55 resistance which is a function of direct current component of current passing therethrough, means including a resistance device for connecting said first named resistance element across said source of anode current, said resistance device being effectively shunted across the output circuit of said electronic tube, said resistance device having a variable tap, means for connecting the audio frequency utilizing load between one end of the last named resistance device and said 60 variable tap to thereby provide for variable transfer of energy from the output of said tube to the utilizing load, and a path of low direct current resistance connected between said variable tap and said end of the last named resistance 65 device whereby variations of the variable tap along said last named resistance vary the effective resistance connected in series between said source and said resistance element to thereby vary the flow of current through the first named resistance 70 element in accordance with variations in

the amount of audio frequency energy transferred from the output of the tube to the audio frequency utilizing circuit.

6. The combination with an audio frequency amplifier of a tone control circuit therefor, including a filter network provided with means for giving to the filter network variable frequency characteristics, said means including an ohmic resistance device having an alternating current resistance which is a function of the direct current component of current passing through it, a source of direct current, means connecting said resistance device across said source of current, an audio frequency utilizing load, means for connecting the load to said audio frequency amplifier, said last named means including a variable device adapted to control the amount of energy transferred from the audio frequency amplifier, said variable device also acting upon operation to vary the amount of current transferred from said source of direct current to said ohmic resistance device whereby the frequency characteristics of said filter network are varied simultaneously with variations in the energy transferred between the audio frequency amplifier and the utilizing load.

7. In an audio frequency transmission system having input terminals for connection to a source of audio frequency voltage and output terminals for connection to an audio frequency utilizing device, a network including a filter unit provided with resistance means the alternating current resistance of which is a function of the direct current component of current passing therethrough, said network having a frequency characteristic depending upon the magnitude of the alternating current resistance of said resistance means, a source of direct current and means including a variable resistance device for connecting said resistance means across said source of direct current whereby current from said last named source flowing through said resistance means may be controlled to thereby vary the frequency characteristic of the network.

8. A transmission network including a plurality of resistance elements whose alternating current resistance depends upon the direct current component of current flowing therethrough, said network having a frequency discriminating characteristic dependent upon the alternating current resistance of said resistance elements, means for providing a flow of direct current through said resistance elements and means for adjusting the magnitude of said direct current flow through said resistance elements to thereby control the frequency characteristic of said network.

9. In a transmission network for coupling a source of energy to a utilizing circuit, a filter circuit having a resistance element whose alternating current resistance depends upon the direct current components of current passing therethrough, said filter circuit having a frequency discriminating characteristic which is dependent upon the alternating current resistance of said resistance element, means for providing direct current flow through said resistance element and means for adjusting the magnitude of the direct current flow through said resistance element to thereby control the frequency characteristic of said filter circuit, said last named means also acting to control the amount of energy transferred from said source to said utilizing circuit through the transmission network.
